Primary Examiner — George D. Kirschbaum*Assistant Examiner* — Jennifer L Watkins(74) *Attorney, Agent, or Firm* — Knobbe Martens Olson & Bear LLP(57) **CLAIM**

The ornamental design for a padded tape, as shown and described.

DESCRIPTION

FIG. 1 is a perspective view of a padded tape in accordance with the present invention.

FIG. 2 is a top view of the padded tape of FIG. 1.

FIG. 3 is a bottom view of the padded tape of FIG. 1.

FIG. 4 is a front view of the padded tape of FIG. 1.

FIG. 5 is a back view of the padded tape of FIG. 1.

FIG. 6 is a left end view of the padded tape of FIG. 1.

FIG. 7 is a right end view of the padded tape of FIG. 1.

FIG. 8 is a perspective view of the padded tape of FIG. 1 in a roll shape.

FIG. 9 is a top view of the padded tape of FIG. 8.

FIG. 10 is a bottom view of the padded tape of FIG. 8.

FIG. 11 is a right end view of the padded tape of FIG. 8.

FIG. 12 is a left end view of the padded tape of FIG. 8.

FIG. 13 is a back view of the padded tape of FIG. 8; and,

FIG. 14 is a front view of the padded tape of FIG. 8.
